DESIGN FOR A KNITTED SHOE OR SIMILAR ARTICLE

Fred Gluck, New York, N. Y.

Application November 3, 1939, Serial No. 88,020

Term of patent 3½ years

To all whom it may concern:

Be it known that I, Fred Gluck, a citizen of Germany, residing in the city of New York, county of New York, and State of New York, have invented a new, original, and ornamental Design for a Knitted Shoe or Similar Article, of which the following is a specification, reference being had to the accompanying drawing, forming part thereof.

Fig. 1 is a plan view of a knitted shoe or similar article showing my new design.

Fig. 2 is a side elevational view thereof.

I claim:

The ornamental design for a knitted shoe or similar article, substantially as shown.

FRED GLUCK.
